UNITED STATES PATENT OFFICE.

ALVIN C. BLADES, OF CRISFIELD, MARYLAND, ASSIGNOR OF ONE-THIRD TO C. E. COLLINS AND ONE-THIRD TO C. C. WARD, BOTH OF CRISFIELD, MARYLAND.

SIGNAL LAMP.

1,418,615.

Specification of Letters Patent. Patented June 6, 1922.

Application filed February 13, 1922. Serial No. 536,083.

To all whom it may concern:

Be it known that I, ALVIN C. BLADES, a citizen of the United States, residing at Crisfield, in the county of Somerset, in the 5 State of Maryland, have invented a new and useful Signal Lamp, of which the following is a specification.

This invention relates to a combination tail light and signal lamp for motor vehicles. 10 One of the objects of the invention is to provide a lamp which will serve the function of a tail light, and that of a signal lamp either simultaneously, jointly, or severally.

Another object of the invention is to provide means whereby the conventional tail light may be readily converted into a lamp which in addition to its function as a tail light will serve also as a signal lamp.

The above and other objects of the invention are attained by the construction illustrated in the accompanying drawings which form a part of this specification.

Figure 1 is an elevation of my lamp.

Figure 2 is a disassembled view of my 25 lamp.

Figure 3 is a sectional view of a modified construction of my lamp.

Referring to the drawings, 5 indicates the conventional tail light. This comprises a 30 casing 6, the side of which is provided with an opening 7, a socket 8, and a bulb 9. The face of the casing is usually provided with a red colored glass which is retained within the beaded edge 10 of the casing by means 35 of a spring wire 11. The cord 12 leads to the wiring system of the motor car.

The remaining structure shown in Figure 2 constitutes a unitary readily removable mechanism which may be easily attached to the conventional tail light and thereby convert the lamp into a combination tail and signal lamp. This structure comprises a cylindrical casing 13, provided with an exterior flange 14 at one end and a 45 beaded edge 15 at the other end. This casing is provided with a partition 16 comprising two parts at right angles to each other. One part 17 serves to close one-half of the rear face of the casing, and the other 50 part 18 serves to divide the cylindrical casing longitudinally into two chambers. The casing 13 is thus divided into two chambers, one of which 24 is open at both ends, the other chamber 25 being open only at the 55 face end of the casing.

A socket 26 is inserted in the chamber 25 through an opening in the casing 13. The socket receives the signal bulb 27. 19 constitutes an opaque stencil plate which is provided with an opening 20 and a signal stencil 21. 22 is a red colored lens. The plate 19 and lens 22 fit into the beaded edge 15 of the casing 13 and are retained therein by the spring wire 23. The cord 28 leads from the signal lamp socket 26 to the wiring system 65 of the vehicle.

The assembly of the device is obvious. The lens that is held in the bead 10 of the tail light casing by means of the wire spring 11 is removed. The flange 70 14 of the casing 13 is then inserted in the bead 10 and the wire spring 11 is inserted so as to serve to retain the casing 13 in place. When the device is assembled, the tail light is converted into a combination tail and 75 signal lamp. Without interfering with the conventional functions of the tail light, a simple and inexpensive structure is made to serve the additional function of a signal lamp. It will be noted that when assembled, the casing 13 is positioned in such a manner that the tail light 9 emanates its illumination through the opening 20 and also illuminates the license tag through the opening 7 in the conventional manner. 80 When desired the signal lamp 27 is made to illuminate the stop signal. The lamp 27 may be operated in any manner well known in the art such as by a manual switch, by a 85 brake operated switch, or the like.

Figure 3 is a modification of the invention in which the partition 29 is curved in such a manner as to reflect the light from the signal lamp 27.

I claim:

1. The combination of a tail light casing for motor vehicles, said casing having an open face, with a signal casing provided with means for dividing said signal casing into two longitudinal chambers, means in one of said chambers for receiving a signal light, and means for readily attaching and detaching said signal casing to the open face of said tail light casing.

2. The combination of a tail light casing having an open face with a signal casing comprising two longitudinal chambers, means in one of said chambers for receiving a signal lamp, an opaque closure at one end of said chamber and means for attaching 105

the signal casing to the open face of the tail light casing.

3. An article of manufacture comprising a hollow casing, means for longitudinally dividing said casing into a plurality of chambers, one of said chambers being open at both ends, and at least one of said chambers being provided with an opaque closure, a lamp receiving socket in said last-mentioned chamber, and means at one end of

said casing adapted to cooperate with a tail light casing to hold said casings together, in axial alignment.

4. The structure recited in claim 3, the last-mentioned chamber being provided at its forward end with a signalling indicia.

In testimony whereof I hereunto affix my signature.

ALVIN C. BLADES.
